UNITED STATES PATENT OFFICE.

ABBOT AUGUSTUS LOW, OF BROOKLYN, NEW YORK.

DESIGN FOR A BADGE.

SPECIFICATION forming part of Design No. 22,696, dated August 15, 1893.

Application filed June 29, 1893. Serial No. 479,172. Term of patent 14 years.

To all whom it may concern:

Be it known that I, ABBOT AUGUSTUS LOW, a citizen of the United States, residing in the city of Brooklyn, in the county of Kings and 5 State of New York, have invented and produced a new and original Design for Badges, of which the following is a specification, reference being had to the accompanying drawing, in which the figure represents a front view 10 of the badge.

The leading feature consists in the representation of a section *a*, of a tree, from a

portion of which the bark has been removed, and which has been marked as a monument. Surrounding the representation of the portion of marked tree a simple border *b*, is arranged, either with or without ornamentation of leaves *c*.

What I claim is—

The design for badges herein set forth.

ABBOT AUGUSTUS LOW.
